UNITED STATES PATENT OFFICE

2,195,639

AIR CIRCULATOR FOR REFRIGERATOR CARS

Wallace E. Baillie, McDonald, Pa., assignor, by
mesne assignments, to Standard Railway
Equipment Manufacturing Company, a corpora-
tion of Delaware

Application September 23, 1937, Serial No. 165,309

6 Claims. (Cl. 62—19)

The invention relates to insulated railway refrigerators used to transport perishable commodities, such as vegetables, fruits, berries, meats, eggs, frozen fish, etc., and to maintain such commodities while in transit within a predetermined range of temperature, thus necessitating the use of a cooling means in the summer and a heating means in the winter. It has been found that perishable commodities which have not been allowed to get too cold (freeze) or too hot (bake) have a high market value because they have a longer storage life.

In a modern refrigerator car a bulkhead separates a refrigerant chamber from the lading compartment and is provided with apertures adjacent the ceiling and floor of the car, respectively. Means are provided to induce a convection circulation of air between the refrigerant chamber and lading compartment through said apertures. Ice is used as such means when it is desired to cool the lading and a stove is used when it is desired to warm the lading, but the movement of the air in either of such cases is usually quite slow and sluggish and, therefore, not satisfactory in very cold or very hot weather and sometimes allows the lading to freeze or bake.

An object of the invention is to augment the movement of the circulating air and thus obtain a more even temperature of the lading during transit and a colder lading when ice is used and a warmer lading when a heater is used.

In the drawings:

Fig. 1 shows a longitudinal section of a part of a refrigerator car having my improved means for augmenting the circulation of air therein.

Fig. 2 shows an elevation of the bulkhead and my improvement in the upper part thereof and in the lower part thereof shows a section on line 2—2 of Fig. 1.

Fig. 3 shows a plan view of the refrigerant chamber and my improvement.

Fig. 4 shows an elevation of the fan design of my improvement and portions of the associated parts of the car.

Fig. 5 is a plan view of Fig. 4.

Fig. 6 is a side elevation of Fig. 4.

Fig. 7 is a section on line 7—7 of Fig. 4.

Fig. 8 is a plan view of a modified construction and portions of the associated parts of the car.

Fig. 9 shows the swinging arm attachment of the modified construction to the car.

Fig. 10 is a side elevation of Fig. 9.

In the form of my invention illustrated the refrigerator car is provided with a bulkhead 2 sep-

arating the refrigerant chamber 3 from the lading compartment 4. The bulkhead 2 is provided with an aperture adjacent the floor 6 of the car and an aperture 7 adjacent the ceiling 8 of the car with a solid wall 9 therebetween.

A refrigerant is supported by the grates 12 in the refrigerant chamber 3 in spaced relation to the floor 6 of the car and the basket (or netting) 13 spaces the refrigerant from the end wall 14 and bulkhead 2 to provide the flues 16—17. The apertured floor rack 18 supports the lading so as to provide the space 20 which communicates with the flues 16—17. A refrigerant, such as ice, in the refrigerant chamber induces a convection circulation of air from the flues 16—17 through the flue space 20 and the apertures 21 in the floor rack 18, and as the air is warmed by the lading, it rises and passes through the bulkhead upper opening 7, and thence through the flues 16—17, and being cooled by the refrigerant, repeats the convection cycle.

When a stove or other heater is placed in the refrigerant chamber a convection circulation of air is induced in the opposite direction because the air warmed by the heater rises and falls when cooled by the lading.

The means to augment the circulation of air comprises a plurality of spaced apart vanes 30 positioned in the upper (or lower) aperture in the bulkhead 2 and lying in a plane substantially parallel to the direction of movement of the circulating air. Each vane 30 has one margin thereof pivotally mounted 31 upon a rigid part of the car, such as the members 32 and 33 shown. Some portion of each vane 30 remote from the pivoted margin 31 is yieldingly attached to a rigid part of the car, preferably by the aligned coil springs 35 and 36, wherein the upper spring 35 is suspended from the bracket 37 and the lower spring 36 is supported by the bracket 38. If a plurality of vanes are used each vane is pivotally attached 40 to the upright member 41 for simultaneous operation. The jolting caused by the service movements of the car and the inertia of the vanes causes the vanes to swing around their pivots 31, 45 upwardly or downwardly, and the springs 35—36 return the vanes to their normal substantially horizontal positions. Such action causes the vanes to fan the air in a direction away from the pivot points 31, thus increasing the speed of the 50 circulation of the air. The vanes are held in a substantially horizontal position by their pivots 40, thus providing means to limit the vanes to substantially vertical movements.

Another modification of my invention is shown

wherein a plurality of vanes 50 are yieldingly supported below the grate 12 in the refrigerant chamber 3 preferably by the coil springs 51 which are suspended from the brackets 52 which are shown secured to the grate 12. The vanes 50 extend between and are secured to the spaced apart headers 54. The substantially horizontally disposed arms 55 are pivotally attached 56 to the headers 54 and also pivotally attached 57 to the brackets 58 which are secured to a fixed part of the car, (such as the end wall 59) so that when the jolting caused by the service movements of the car and the inertia of the vanes 50 (and headers 54) cause the vanes to move upwardly or downwardly. The arms 55 provide means to limit the vanes to substantially vertical movements. The unit (comprising the vanes and the headers) is free to rotate about the pivots 56 while the unit swings on the arc from the pivots 57 which is substantially a vertical movement.

Each vane is provided with a substantially horizontally disposed upwardly projecting concave surface provided in the form illustrated by the walls 61 and 62, whereby upon a downward movement of the vanes 50 the concave surfaces of the vanes force air downwardly. See Fig. 10. (Concave is used broadly herein.)

Each vane 50 is also preferably provided with an inclined surface 65 facing toward the lower aperture in the bulkhead 2 provided in the form illustrated by the wall 65—66 whereby upon an upward movement of the vanes 50 the inclined surface 65—66 forces air toward the aperture and under the lading. (See Fig. 10.)

The concave 61—62 and inclined 65—66 surfaces are preferably used in each vane though they may be used independently of each other in separate vanes to augment the circulation of air.

One vane, or a plurality of vanes, may be used and still come within the scope of the invention.

I have shown coil springs in the drawings but a leaf spring or a flexible band (a rubber band, for instance,) may be used.

The accompanying drawings illustrate the preferred form of the invention, though it is to be understood that the invention is not limited to the exact details of construction shown and described, as it is obvious that various modifications thereof, within the scope of the claims, will occur to persons skilled in the art.

I claim:

1. In a refrigerator car having a bulkhead separating a refrigerant chamber from the lading compartment, a refrigerant grate in said chamber, said bulkhead provided with upper and lower apertures so that a refrigerant in said chamber induces a convection circulation of air between said chamber and said compartment, means to augment said circulation of air comprising a vane yieldingly suspended below said grate, said vane provided with a substantially horizontally disposed upwardly projecting concave surface and an inclined surface facing toward said lower aperture so that the service movements of the car cause the inertia of the vane to cooperate with the yielding suspension and move said vane upwardly and downwardly whereby upon the downward movement the concave surface forces air downwardly and upon the upward movement the inclined surface forces air toward said aperture.

2. In a refrigerator car having a bulkhead separating a refrigerant chamber from the lading compartment, a refrigerant grate in said chamber,

- grate, said vane provided with a substantially horizontally disposed upwardly projecting concave surface so that the service movements of the car cause the inertia of the vane to cooperate with the yielding suspension and move said vane upwardly and downwardly whereby upon the downward movement the concave surface forces air downwardly.
5. In a refrigerator car having a bulkhead separating a refrigerant chamber from the lading compartment, a refrigerant grate in said chamber, said bulkhead provided with upper and lower apertures so that a refrigerant in said chamber induces a convection circulation of air between said chamber and said compartment, means to augment said circulation of air comprising a vane yieldingly suspended below said grate, said vane provided with a substantially horizontally disposed upwardly projecting concave surface so that the service movements of the car cause the inertia of the vane to cooperate with the yielding suspension and move said vane upwardly and downwardly whereby upon the upward movement the inclined surface forces air 10 toward said aperture.
6. In a refrigerator car having a bulkhead separating a refrigerant chamber from the lading compartment, a refrigerant grate in said chamber, said bulkhead provided with upper and lower apertures so that a refrigerant in said chamber induces a convection circulation of air between said chamber and said compartment, means to augment said circulation of air comprising a vane yieldingly suspended below said grate, said vane provided with a substantially horizontally disposed upwardly projecting concave surface so that the service movements of the car cause the inertia of the vane to cooperate with the yielding suspension and move said vane upwardly and downwardly whereby upon the upward movement the inclined surface forces air toward said aperture.
10. In a refrigerator car having a bulkhead separating a refrigerant chamber from the lading compartment, a refrigerant grate in said chamber, said bulkhead provided with upper and lower apertures so that a refrigerant in said chamber induces a convection circulation of air between said chamber and said compartment, means to augment said circulation of air comprising a vane yieldingly suspended below said grate, said vane provided with a substantially horizontally disposed upwardly projecting concave surface so that the service movements of the car cause the inertia of the vane to cooperate with the yielding suspension and move said vane upwardly and downwardly whereby upon the upward movement the inclined surface forces air toward said aperture.

WALLACE E. BAILLIE.
